ACCORDION SWITCHBOARD

Aldo Logli, Detroit, Mich.

Application December 24, 1952, Serial No. 22,866

Term of patent 14 years

(Cl. D56—1)

To all whom it may concern:

Be it known that I, Aldo Logli, a citizen of the United States, residing at Detroit, in the county of Wayne and State of Michigan, have invented a new, original, and ornamental Design for an Accordion Switchboard, of which the following is a specification, reference being had to the accompanying drawing, forming a part thereof.

In the drawing:

Figure 1 is a top plan view of an accordion switchboard, showing my design;

Figure 2 is a front elevation thereof; and

Figure 3 is an end elevation thereof.

The dotted line showing on the drawing is for illustrative purposes only.

I claim:

The ornamental design for an accordion switchboard, as shown and described.

ALDO LOGLI.
